UNITED STATES PATENT OFFICE

2,008,072

MACHINE FOR SHAPING SHOE UPPERS

Eric A. Holmgren, Lynn, Mass., assignor to
United Shoe Machinery Corporation, Paterson,
N. J., a corporation of New Jersey

Application August 13, 1934, Serial No. 739,545

19 Claims. (Cl. 12—4)

This invention relates to machines for use in the manufacture of shoes for shaping the upper materials, and is herein illustrated in its application to a machine of the same general type as disclosed in United States Letters Patent No. 1,700,970, granted on February 5, 1929, upon an application of W. C. Baxter, comprising means for shaping over a form and over an insole on the form the heel-end portion of upper materials before the upper and insole are mounted on a last. It is to be understood, however, that in various aspects the invention is not limited to a machine organization of that particular character.

Machines of the type illustrated in the above-mentioned Letters Patent have been provided heretofore with means for pulling the upper lengthwise relatively to the form over which its heel end is shaped, so as to stretch the upper preliminarily before it is mounted on the last and also to draw its heel-end portion tightly about the form to assist in shaping it over the form. Such upper-pulling means is disclosed, for example, in Letters Patent No. 1,913,445, granted upon an earlier application of mine on June 13, 1933. The upper-pulling means therein shown was constructed especially for use in operating on uppers the toe-end portions of which had been previously molded substantially to the shape desired for the finished shoes. An object of the present invention is to provide upper-pulling means constructed for use on uppers the toe ends of which have not been previously molded, and the invention is accordingly herein illustrated as embodied in means of that character, although it will be recognized that in some aspects it is not thus limited in its applicability.

The invention, in one aspect, provides novel means for pulling an upper as above described in such manner that the strains on different portions thereof are substantially equalized, so that it is properly stretched without undesirable distortion of any portion. For this purpose, the construction shown comprises upper-pulling means whereby the forepart of the upper is clamped throughout the greater portion of its width at the tip line and for substantial distances both forwardly and rearwardly of the tip line, the upper-engaging faces of the cooperating clamping members being curved laterally of the upper but extending straight lengthwise of the upper to adapt them for use with substantially the same effect on the uppers of shoes of various styles and sizes. As illustrated also, one of the upper-clamping members, arranged to engage the inner face of the upper, is formed to extend throughout

the greater portion of the length of the forepart of the upper and to hold the latter outspread at the rear of the portion engaged by the cooperating clamping member so as to assist in insuring uniformity in the pulling of the upper.

Further to insure that each upper will be properly stretched without distortion of any portion thereof, and also to insure substantial uniformity in the results obtained in pulling different uppers, the invention provides novel means for positioning the forepart of each upper in proper predetermined relation to the upper-pulling means and the form. In the construction shown this positioning means comprises jig pins arranged to enter jig holes provided in the margin of the upper at the opposite sides of the forepart, preferably in locations substantially at the ends of the tip seam if the upper includes a toe tip, and thus to predetermine the angular relation of the tip line to the upper-pulling means and the form, the jig pins, as illustrated, also determining the position of the forepart of the upper laterally. Further to assist in positioning the upper properly before it is clamped by the upper-pulling means, there is provided means for subjecting it to a comparatively light lengthwise pull about the form and also a heightwise pull about one of the clamp members, such means, as illustrated, comprising springs which act thus on the upper through the jig pins.

To facilitate the use of the machine for shaping uppers of different sizes, and to insure that the upper-pulling means will be properly positioned to operate in the best manner on such different uppers, the invention further provides for positioning the upper-pulling means relatively to the form in accordance with the size of the upper to be operated upon, without special attention on the part of the operator. For shaping the heel ends of uppers of different sizes forms of correspondingly different sizes are preferably utilized, and for the purpose above described the machine is provided with mechanism controlled by each form for positioning the upper-pulling means initially at a distance from the form determined by the size of the form. In the construction shown the above-mentioned jig pins are supported on the upper-pulling means to move therewith, and accordingly by such mechanism the jig pins also are variably positioned in accordance with the sizes of different uppers.

The above and other features of the invention, including also novel means whereby the upper is maintained under tension after it has been pulled and is thereafter released from tension,

and various novel details of construction and combinations of parts will now be more particularly described by reference to the accompanying drawings and pointed out in the claims.

5 In the drawings,

Fig. 1 is a view, partly in right-hand side elevation and partly in section, of a portion of a machine in which the invention is embodied, the parts being shown in the positions which they 10 occupy in pulling the upper;

Fig. 2 is a view similar to Fig. 1 on a larger scale of portions of the structure there shown, the structure as a whole, however, being illustrated for convenience in a position in which the work 15 support is more nearly vertical than in Fig. 1;

Fig. 3 is a section on the line III—III of Fig. 2;

Fig. 4 shows a portion of the structure in front elevation, with parts broken away;

Fig. 5 is a view in left-hand side elevation of 20 the structure shown in Fig. 2;

Fig. 6 is a view similar to Fig. 5, but showing the parts in their initial positions before the work is presented to the machine; and

Fig. 7 is a section on the line VII—VII of Fig. 6.

25 Since in its general organization, except as hereinafter described, the machine herein shown is of substantially the same construction as disclosed in the previously-mentioned Letters Patent, only such parts as it is necessary to refer to for an understanding of this invention will be hereinafter mentioned. The machine is provided with a heel-end form 10 which is substantially coterminous lengthwise with the heel-end portion of the upper materials, and with means 30 for shaping or molding the heel-end portion of the upper over the form and over an insole on the form, the upper-shaping means comprising a heel band 12 (Fig. 1) for clamping and shaping the upper about the rear end and the sides of the form and wipers 14 for wiping the marginal portion of the heel end of the upper inwardly over the insole. There is also provided means (not 35 shown) for driving tacks through holes 16 in the wipers to fasten the marginal portion of the upper to the insole. The proper relation of the insole to the form is determined by pins 18 which project from the form through holes in the insole. The form is detachably supported, as more particularly hereinafter described, on a work support 40 comprising a carrier 20 mounted at 22 on the base of the machine for swinging movement to carry the form with the work from a forwardly inclined work-receiving position (Fig. 1) into position to present the work to the heel band 12 and the wipers 14. This movement of the work support and the operation of the heel band and wipers are effected automatically by mechanism which it is unnecessary to describe for an understanding of the present invention. The upper and the insole are mounted upon the form 10 when the form is in its work-receiving position, and to assist in positioning the heel end of the upper materials in proper relation to the form there is provided a jiggling device 24 having means for engaging the marginal portion of the upper at the extreme heel end in jig holes provided in the upper, and also means for pressing down the rear end of the counter, as disclosed in Letters Patent No. 1,726,833, granted upon an earlier application of mine on September 3, 1929. This jiggling device is in control of the upper as the latter is subjected to a lengthwise pull in the manner hereinafter described, but is withdrawn from its operative position before the work support receives its rearward swinging movement. For con-

venience this device is herein shown (Fig. 1) in the position which it assumes after it has thus been withdrawn from its operative position.

For pulling the upper to stretch it lengthwise and to draw its heel end tightly about the 5 form 10 while the form is in its work-receiving position, there is provided mechanism which is in some respects similar to the construction shown in the above-mentioned Letters Patent No. 1,913,445 and in other respects involves novel 10 features for purposes of the present invention. Such pulling of the upper is effected by engagement with its forepart, the construction herein shown being such as to operate thus by engagement with uppers the toe-end portions of which 15 have not been previously molded. For the purpose in view the forepart of the upper is clamped between members 26 and 28 which act respectively on the inner and outer faces of the upper materials, both of these members being supported on an angularly shaped carrier 30 having a rearwardly extending lower portion supported by a 20 rod 32 and a shaft 34 upon the upper ends of substantially parallel links 36 and 38. These links at their lower ends are supported for swinging movements on rods 40 and 42 respectively which are mounted on a bracket 44 supported for adjustment about an upright rod 46, this rod being mounted in a bracket 48 secured on the front of the work support member 20. Adjustment of 30 the bracket 44 about the rod 46 serves to vary the positions of the upper-pulling clamp members 26 and 28 laterally of the form 10 for operating respectively upon right and left uppers. The bracket 44 is held in proper adjusted position by 35 screws 50, one at each side thereof (Fig. 4), which engage lugs 52 on the bracket 48.

The clamp member 26 comprises a plate curved laterally of the upper and formed to engage the upper materials throughout the greater portion 40 of the width of the forepart, the plate being straight lengthwise of the upper in view of its intended use on uppers of various styles and sizes and being of such length as to extend throughout the greater portion, at least, of the 45 length of the forepart of the upper so as to maintain the top of the forepart outspread and thus assist in avoiding undue localization of the strain on the upper as it is pulled. This plate is secured to a block 54 fastened to a rearwardly extending 50 arm of the carrier 30. The clamp member 28 is movable upwardly and downwardly into and out of clamping relation to the plate 26 and has a leather facing 56 for engaging the upper, this clamp member being curved laterally of the upper 55 similarly to the plate 26. For the purpose of such upward and downward movement the clamp member 28 is supported on a slide 58 movable along guideways on the carrier 30, and between the clamp member and the slide there are interposed springs 60 which are yieldable more or less in the clamping of the upper. The slide 58 is operated by turning movement of the shaft 34 above referred to as affording a connection between the carrier 30 and the link 38, the shaft 65 having fast thereon a crank arm or lever 62 for thus operating it. The shaft 34 has fast thereon a sleeve 63 (Fig. 4) which carries a crank pin 64 connected by curved links 66 to the slide 58. Movements of the crank arm 62 in opposite 70 directions are limited by stops 68 and 70 on the carrier 30. The initial position of the crank arm is determined by the stop 68, as illustrated in Fig. 6, and the stop 70 limits the movement of the crank arm in the direction to clamp the upper 75

(Fig. 5). When the crank arm 62 is in the position determined by the stop 70, the crank pin 64 is on dead center, so that the parts remain in clamping positions when the operator releases the crank arm. By reference to Figs. 2 and 5 it will be seen that the clamp member 28, through its leather facing 56, engages the upper at the tip seam and also for a considerable distance forwardly of the tip seam as well as more or less rearwardly thereof to hold the upper in the vicinity of the tip seam against distortion in the upper-pulling operation. The member 26, moreover, extends rearwardly a considerable distance beyond the member 28 to maintain the forepart of the upper outspread laterally at the rear of the clamped portion, so as to assist in avoiding distortion of the upper as it is pulled.

In the construction herein shown the carrier 30 with its upper-clamping means is held initially in an upper-receiving position comparatively near the form 10 (Fig. 6) by a spring 72 connected at one end to the bracket 44 and at the other end to the link 38, this position of the carrier being determined in accordance with the size of the upper by means hereinafter described. The carrier is operated to pull the upper by a pawl-and-ratchet device comprising a plate 74 (Fig. 6) secured to the link 38 between spaced portions of the link and having ratchet teeth 76 thereon, and pawls 78 and 80 arranged to engage the teeth 76 and pivoted on a pin 82 on a pawl carrier 84 which is mounted to swing on the rod 42. The pawls 78 and 80 are arranged in staggered relation to each other for greater precision. For operating the pawl carrier 84 there is provided a crank arm 86 (Figs. 2 and 4) fast on a rock shaft 88 mounted in the bracket 44, this rock shaft being provided with a crank pin 90 connected by a link 92 to the pawl carrier. The pawls 78 and 80 are controlled respectively by springs 94 and 96 which tend to swing them toward the ratchet teeth, the spring 94 being connected to a pin 98 mounted in a lug on the pawl 78 and extending past the pawl 80. Initially both pawls are held out of engagement with the ratchet teeth (Fig. 6) by a stop 100 adjustably mounted in a bracket 102 depending from the bracket 44, this stop being arranged to engage a pin 104 on the pawl 80. The stop 100 thus acts directly on the pawl 80, and this pawl by engagement with the pin 98 on the pawl 78 holds the latter also retracted from engagement with the ratchet teeth. It will be understood that when the operator swings the crank arm 86 forwardly toward him the pin 104 leaves the stop 100 and the pawls then engage the ratchet teeth and are operative in further movement of the crank arm to swing the link 38 and thereby impart forward pulling movement to the carrier 30. The crank arm 86 carries a spring plunger 106 arranged to be engaged initially by a lug 108 (Fig. 2) on the bracket 44 to hold the crank arm in its initial position and yieldable to permit the forward movement of the crank arm, the latter being shown in Fig. 2 as having received some forward movement. A stop 110 on the bracket 44 serves to prevent forward movement of the crank arm 86 beyond a predetermined position.

The amount of upper-pulling movement imparted to the carrier 30 in pulling each upper by use of the construction herein shown is under control of the operator, and it is contemplated that such upper-pulling movement of the carrier may be effected in successive steps by re-

peated movements of the crank arm 86. To hold the carrier 30 against retractive movement from the position which it assumes in response to any forward movement of the crank arm 86 there are provided holding pawls 112 and 114 (Fig. 6) arranged to engage the teeth 76, these pawls being arranged in staggered relation for greater precision. The pawl 112 is fast on a rock shaft 116 mounted in the bracket 44, and the pawl 114 is loose on this rock shaft. Secured to the rock shaft 116 is a bell-crank lever 118 controlled by a spring 120 which tends to swing the pawl 112 toward the ratchet teeth. This pawl carries a leaf spring 122 which bears on a pin 124 carried by the pawl 114 and accordingly serves to swing the pawl 114 into engagement with the ratchet teeth as the pawl 112 is moved into engagement with the teeth by the spring 120. For swinging the pawls out of engagement with the ratchet teeth to permit the return of the carrier 30 to its initial position there is provided a link 126 pivoted at 128 to the hub of the crank arm 86 and provided at its lower end with a slot 130 in which lies a pin 132 carried by one arm of the bell-crank lever 118. When the parts are in the positions illustrated in Fig. 6 the pin 132 is at the lower end of the slot 130 and the link 126 holds the bell-crank lever 118 in position to maintain the pawl 112 out of engagement with the ratchet teeth, the pawl 114 being at the same time held out of engagement with the teeth by contact of the pawl 112 with the pin 124 on the pawl 114. When the crank arm 86 is swung into position to effect the clamping of the upper, the link 126 is carried downwardly and releases the bell-crank lever 118 so as to permit the pawls 112 and 114 to be swung into engagement with the ratchet teeth, as illustrated in Fig. 5. The pawls are thus rendered effective to maintain the pull on the upper when the carrier 30 is operated by the crank arm 86. When the crank arm 86 is swung into position to unclamp the upper after the completion of the cycle of operations of the machine, the pawls 112 and 114 are returned to their idle positions by the link 126 to permit the carrier 30 to be returned to its starting position by the action of the spring 72 thereon.

To assist in insuring that each upper will be properly clamped and will be properly stretched without distortion of any part thereof, having regard to the correct lines of the finished shoe, the machine is further provided with means for positioning the foreparts of all uppers of the same size and style uniformly in the same correct relation to the heel-end form 10 and to the clamp members 26 and 28 before the uppers are clamped by these members. This means comprises jig pins 134 and 136 (Fig. 3) arranged to enter jig holes provided in the opposite side margins of the forepart of the upper, preferably in locations substantially at the ends of the tip seam if the upper is provided with a toe tip, these jig holes being adapted for use later in positioning the toe end of the upper in proper relation to means for shaping that portion of the upper. The jig pins 134 and 136 are supported respectively on arms 138 and 140 (Figs. 2, 4 and 5) which are mounted on a rod 142 extending transversely of the carrier 30 at the upper end of the latter, the rod being supported at its opposite ends on arms 144 and 146 pivotally mounted at 148 and 150 respectively on the carrier 30. The arms 138 and 140 are each separately adjustable about the rod 142, and the arms are secured in adjusted relation 75

to members 152 and 154 fast on the rod 142 by clamp screws 156 and 158 threaded respectively in the different arms and extending through slots in the members 152 and 154. The rod 142 is mounted to turn in the arms 144 and 146, and mounted in these arms are spring plungers 160 and 162 which by engagement with the members 152 and 154 tend to swing the arms 138 and 140 and the jig pins thereon in an upward direction. Such upward movement of the arms is limited by a bar 164 (Figs. 2 and 3) associated with the jig pin 136, as more particularly hereinafter described.

Fast on the arm 144 is a depending arm 166 (Figs. 4, 5 and 6) to the lower end of which is connected a spring 168, this spring tending to swing the arms 144 and 146 and the rod 142, together with the arms 138 and 140 and the jig pins thereon, in a forward direction away from the form 10. Initially the arm 166 is held by the spring 168 against a stop 170 (Fig. 6) on the carrier 30. The jig pins 134 and 136 are thus maintained by the spring 168 in positions a little farther from the form 10 than the jig holes in the upper after the upper has been mounted on the form, and they are also maintained by the spring plungers 160 and 162 in positions higher than required to enter the jig holes. Accordingly the operator swings the arms 144 and 146 rearwardly and swings the arms 138 and 140 downwardly before mounting the upper on the jig pins, and when he releases the different arms the jig pins spring both forwardly and upwardly, thereby imparting a light forward pull to the upper about the form 10 and also an upward pull to draw it tight over the clamping plate 26 while locating the tip seam in correct relation to the form and the clamping means.

The jig pin 134 is preliminarily adjustable in directions lengthwise of the upper along a slot 172 (Fig. 6) in the arm 138, and for this purpose is provided with a diametrically enlarged portion 174 (Fig. 3) having slots cut in its opposite sides to receive the portions of the arm 138 located at the opposite sides of the slot 172. Threaded on a stem 176 extending from the enlarged portion 174 is a nut 178 which by engagement with the arm 138 clamps the jig pin 134 in adjusted position. The opposite jig pin 136 is similarly provided with an enlarged portion 180 slotted to receive spaced portions of the arm 140 at opposite sides of a slot 181 (Fig. 2) in the arm and having a stem 182 projecting therefrom. Mounted on this stem is a bushing 184 which bears on the outer side of the arm 140 and has a reduced portion 186 extending loosely through a slot 188 in the previously mentioned bar 164. Threaded on the stem 182 is a nut 190 which presses the bushing 184 against the arm 140 and therefore clamps the jig pin in adjusted relation to the arm 140 while permitting upward and downward swinging movements of the arm relatively to the bar 164. It will be understood that the limiting of the upward swinging movements of the arms 138 and 140 results from engagement of the bar 164 with the reduced portion 186 of the bushing 184 at the upper end of the slot 188 in the bar.

The bar 164 is a part of means provided for indicating to the operator when each upper has been pulled the amount required. The bar is secured at its lower end portion to a bracket 192 (Figs. 2 and 4) having rearwardly extending upper and lower arms 194 and 196, the arm 196 being supported for swinging movement on a rod 198 which is mounted in the bracket 44. This permits the bar 164 to be swung forwardly through its above-described connections to the arm 140 when the

carrier 30 is moved forwardly to pull the upper. Mounted for swinging movements on a stud 200 on the bracket 44 is a member 202 to which is fastened an upwardly extending arm 204 having a laterally projecting pointer 206 at its upper end. 5 Carried by the arm 194 is a pin 208 which extends into a slot 210 formed in the member 202, so that as the bar 164 is swung forwardly as above described the pointer 206 is swung by the bar in the same direction. A light spring 212 connected to the lower end of the member 202 insures that the pin 208 will always engage the arm 194 at one side of the slot 210 for the sake of greater accuracy in the control of the pointer 206. This pointer cooperates with a scale on a plate 214 which is 15 fastened on the segmentally shaped upper end of a lever 216 supported on the above-mentioned stud 200 and adjustable about the stud. In the lower end of the lever 216 is a segmental slot 218 through which extends the previously mentioned 20 rod 198, and threaded on the end of this rod is a thumb nut 220 which serves to clamp the lower end of the lever 216 in adjusted position against a shoulder on the rod 198. The arm 216 is thus held stationary during the pulling of the upper 25 and the pointer 206 moves relatively to it. The scale on the plate 214 may be graduated to indicate different shoe sizes. It is contemplated that in the use of this mechanism the operator will pull one upper an amount which in his judgment 30 is sufficient for the purpose in view and will then adjust the lever 216 until the pointer 206 is over that mark on the scale corresponding to the size of that particular upper. Thereafter the lever 216 will be left in the same position in pulling 35 other uppers, each upper being pulled by forward movement of the carrier 30 until the pointer 206 is over that mark on the scale which corresponds to the size of the upper. This provides for substantial uniformity in the stretching of the 40 different uppers.

As previously stated, the carrier 30 with its upper-clamping and controlling means is held by the spring 12 initially in a position comparatively near the form 10. It will be evident that in order 45 that the tip seams of uppers of different sizes will be located in substantially the same relation to the clamp members 28 and 28, and in order that the jig pins 134 and 136 will be so located that they may be readily connected with the different sized 50 uppers and will subject each upper to a light forward pull in the manner previously described prior to the clamping of the upper, the carrier 30 should be located at different distances from the form 10 corresponding to differences in sizes of the 55 uppers. Preferably forms 10 of different sizes will be used in operating on the different sized uppers, and as herein illustrated mechanism controlled by the different forms is provided for thus variably positioning the carrier 30. Each form 10 is 60 detachably mounted on a pin 222 (Fig. 6) at the upper end of a bar 224 which is mounted in the work carrier 20, a bushing 226 being provided between the pin and the form. A portion 228 of the bar 224 is provided with straight upwardly 65 extending faces arranged to engage corresponding faces on the form and thus to prevent the form from turning relatively to the bar. A lower face 230 at the rear end of the form is supported on the upper end face of the work carrier 20. Each 70 form has in its forward end a slot 232 to receive the upper end of one arm 234 of a bell-crank lever 236 which is pivoted at 238 on the bracket 44, this lever having a forwardly extending arm 240 in which is adjustably mounted a screw 242 75

arranged to bear at its lower end on a bracket 244 fastened to the link 38. The arm 234 of the bell-crank lever 236 is arranged to bear on each form 10 at the bottom of the slot 232 in the form, so that the form determines the limit of upward swinging movement of the arm 240 of the lever. The swinging of the link 38 under the influence of the spring 72 is accompanied by upward movement of the forward end of the bracket 244, and it will be evident that the link can be swung rearwardly only as far as permitted by contact of the bracket with the screw 242 when the arm 240 is at the limit of its upward movement. The different sized forms 10 are so constructed that through this mechanism the initial position of the carrier 30 will be varied in accordance with the size of the form, and accordingly the upper-pulling means will be variably positioned, under control of the different forms, as required for operating on the uppers of different sizes.

Each form 10 is locked in operative position on the bar 24 by a yoke-shaped member 246 (Figs. 6 and 7) slidingly mounted in substantially horizontal guideways formed in opposite sides of the portion 228 of the bar, the rear end of the member 246 extending into a slot 248 in the form to lock the latter. The member 246 is held yieldingly in locking position by a spring-pressed plunger 250 mounted in the portion 228 of the bar 224. To unlock the form when it is desired to remove it, use is conveniently made of the previously mentioned bell-crank lever 236. For this purpose the arm 234 of the bell-crank lever carries a pin 252 projecting from the opposite sides of the arm and arranged to engage fingers 254 which project downwardly from a member 256 fastened to the yoke member 246. By depressing the arm 240 of the bell-crank lever 236 the pin 252 is made to engage the fingers 254 and to slide the yoke member 246 forwardly far enough to unlock the form. It will be evident that this can be done only when the carrier 30 of the upper-pulling means is in such a forward position as to provide sufficient space between the bracket 244 and the screw 242 to permit the necessary downward movement of the arm 240. The carrier can be readily moved to this position by the operator when there is no work in the machine. By reference to Figs. 6 and 7 it will be evident that the member 256 by engagement with the portion 228 of the bar 224 serves to limit rearward movement of the yoke member 246 under the influence of the spring plunger 250.

In the use of the machine, the operator mounts the upper materials about the heel-end form 10, a form corresponding to the size of the uppers to be operated upon having already been inserted in the machine, and positions the forepart of the upper between the open clamp members 26 and 28. He then swings the arms 144 and 146 rearwardly and the arms 138 and 140 downwardly until the jig pins 134 and 136 are in positions to have the upper mounted thereon, and after mounting the upper on the pins releases the several arms, whereupon the spring 168 acts through the pins to subject the upper to a light lengthwise pull so as to draw its heel end closely about the form 10 and the spring plungers 160 and 162 act through the pins to draw the forepart of the upper tightly about the clamp member 26. By means of the jig pins the tip seam of the upper is thus located in predetermined angular relation to the clamp members and in predetermined relation also to the form 10, and the forepart of

the upper, moreover, is positioned laterally in predetermined relation to the clamp members. With the upper thus held under light tension by the jig pins the operator mounts an insole on the form in the position determined by the pins 18. The jigging device 24 may then be utilized to position the counter and the heel end of the upper more accurately, in the manner disclosed in the previously mentioned Letters Patent No. 1,726,833.

By swinging the crank arm 62 the operator next moves the lower clamp member 28 into clamping relation to the upper, the pawls 112 and 114 being released by the movement of the crank arm so that they are swung into operative relation to the ratchet teeth 16. By movements of the crank arm 62 the operator then operates the upper-clamping means, through the pawl-and-ratchet mechanism controlled by this arm, to subject the upper to a forward pull, one or the other of the pawls 112, 114 holding the clamping means in any position to which it is thus moved. In the upper-pulling operation the pointer 206 moves along the scale plate 214, and the operator terminates the pulling movement when the pointer arrives at the point on the scale corresponding to the size of upper. While the upper is thereafter held under tension by the upper-pulling means the operator starts the power operation of the machine, whereupon the shoe support and the upper-pulling means are swung rearwardly and the machine operates to shape the heel-end portion of the upper materials over the form and to fasten them to the insole in the manner disclosed in the previously mentioned Letters Patent. After the shoe support has been swung forwardly again at the completion of the upper-shaping operation, the operator swings the crank arm 62 reversely to unclamp the upper, thereby also withdrawing the holding pawls 112, 114 from operative position so that the spring 72 is permitted to move the upper-pulling means rearwardly to the position determined in accordance with the size of the form 10 by the bell-crank lever 236. Thereafter the operator disconnects the upper from the jig pins and removes the shoe materials from the machine. It is contemplated that they will preferably next be presented to a machine such as disclosed in Letters Patent No. 1,968,146 granted upon an application of mine on July 31, 1934, for shaping the forepart of the upper.

Having described the invention, what I claim as new and desire to secure by Letters Patent of the United States is:

1. In a machine for shaping shoe uppers, the combination with means for shaping over a form corresponding to a portion only of a last the heel-end portion of an upper the toe end of which is in unmolded condition, of means for subjecting the upper to a lengthwise pull relatively to said form, said upper-pulling means comprising cooperating upper-clamping members having upper-engaging faces curved laterally of the upper for engaging it over the greater portion of its width and arranged to extend straight lengthwise of the upper substantial distances both forwardly and rearwardly of the tip line.

2. In a machine for shaping shoe uppers, the combination with means for shaping over a form corresponding to a portion only of a last the heel-end portion of an upper the toe end of which is in unmolded condition, of means for subjecting the upper to a lengthwise pull relatively to said form, said upper-pulling means comprising co-

operating upper-clamping members having upper-engaging faces formed to extend straight lengthwise of the upper and curved laterally of the upper for engaging it over the greater portion of its width, the upper-engaging face of one of said members being arranged to extend throughout the greater portion of the length of the forepart of the upper opposite the inner face of the upper.

10. 3. In a machine for shaping shoe uppers, the combination with an upper-shaping form substantially coterminous lengthwise with the heel-end portion of an upper, and means for shaping over said form the heel end of an upper the toe-end portion of which is in unmolded condition, of means for subjecting the upper to a lengthwise pull relatively to said form, said upper-pulling means comprising cooperating upper-clamping members arranged to engage the forepart of the upper respectively on its inner and outer faces, the member engaging the inner face of the upper having its upper-engaging face formed to extend throughout the greater portion of the width of the forepart and also to extend straight lengthwise of the upper rearwardly of the other clamping member for holding the top of the forepart of the upper outspread as the pull is applied.

4. In a machine for shaping shoe uppers, the combination with means for shaping the heel-end portion of an upper over a form, of cooperating clamp members arranged to clamp the forepart of the upper between them and movable relatively to said form to pull the upper lengthwise, a retaining device for holding said members against retractive movement, a controlling member movable by the operator to cause said clamp members to clamp an upper and thereafter to release the upper, and means for rendering said retaining device operative by the movement of said controlling member in a direction to cause the clamping of the upper and for rendering it inoperative by the movement of said member in a direction to cause the release of the upper.

5. In a machine for shaping shoe uppers, the combination with means for shaping the heel-end portion of an upper over a form, of cooperating clamp members arranged to clamp the forepart of the upper between them, means for moving said members in a direction lengthwise of the upper to pull the upper relatively to the form, a pawl-and-ratchet device for holding said members against retractive movement and for thus maintaining the upper under tension, a crank arm for moving one of said clamp members relatively to the other into and out of upper-clamping position, and connections between said crank arm and the pawl-and-ratchet device for rendering said device operative when the upper is clamped by said members and for rendering it inoperative when the upper is released by said members.

6. In a machine for shaping shoe uppers, the combination with means for shaping the heel-end portion of an upper over a form, of cooperating clamp members arranged to clamp the top of the forepart of the upper between them in the vicinity of the tip seam and movable relatively to said form to pull the upper lengthwise, and means for predetermining by engagement with the upper the angular relation of the tip seam to said clamp members before the upper is clamped.

7. In a machine for shaping shoe uppers, the combination with means for shaping the heel-

end portion of an upper over a form, of cooperating clamp members arranged to clamp the top of the forepart of the upper between them in the vicinity of the tip seam and movable relatively to said form to pull the upper lengthwise, and members arranged to engage the marginal portion of the upper in jig holes located substantially at the ends of the tip seam for predetermining the angular relation of the tip seam to said clamp members before the upper is clamped.

8. In a machine for shaping shoe uppers, the combination with means for shaping the heel-end portion of an upper over a form, of cooperating clamp members arranged to clamp the top of the forepart of the upper between them in the vicinity of the tip seam and movable relatively to said form to pull the upper lengthwise, and jig pins arranged to engage the marginal portion of the upper in jig holes provided therein at the opposite sides of the forepart and thereby to predetermine the angular relation of the tip seam to said clamp members and also the position of the forepart of the upper laterally with respect to said members.

9. In a machine for shaping shoe uppers, the combination with means for shaping the heel-end portion of an upper over a form, of cooperating clamp members arranged to clamp the forepart of the upper between them and movable relatively to said form to pull the upper lengthwise, and means movable relatively to said clamp members to subject the upper to a comparatively light lengthwise pull about the form before the upper is clamped by said members.

10. In a machine for shaping shoe uppers, the combination with means for shaping the heel-end portion of an upper over a form, of cooperating clamp members arranged to clamp the top of the forepart of the upper between them in the vicinity of the tip seam and movable relatively to said form to pull the upper lengthwise, and spring-controlled members arranged to engage the upper in jig holes provided substantially at the ends of the tip seam for predetermining the angular relation of the tip seam to said clamp members and for subjecting the upper to a comparatively light lengthwise pull about the form before it is clamped by said clamp members.

11. In a machine for shaping shoe uppers, the combination with means for shaping the heel-end portion of an upper over a form, of cooperating clamp members arranged to clamp the forepart of the upper between them and movable relatively to said form to pull the upper lengthwise, jig pins arranged to engage the marginal portion of the upper in jig holes provided therein at the opposite sides of the forepart and thereby to predetermine the relation of the forepart of the upper to said form and clamp members, and spring means for subjecting the upper through said jig pins to a comparatively light pull to position it in proper relation to said form and clamp members before the upper is clamped by said members.

12. In a machine for shaping shoe uppers, the combination with means for shaping the heel-end portion of an upper over a form, of cooperating clamp members arranged to engage the forepart of the upper respectively on its inner and outer faces and movable relatively to said form to pull the upper lengthwise, and means for pulling the forepart of the upper heightwise about the clamp member engaging its inner face before the upper is clamped.

13. In a machine for shaping shoe uppers, the combination with means for shaping the heel-end portion of an upper over a form, of cooperating clamp members arranged to clamp the top 5 of the forepart of the upper between them in the vicinity of the tip seam and movable relatively to said form to pull the upper lengthwise, jig pins arranged to engage the upper in jig holes provided therein in locations substantially at the 10 ends of the tip seam for predetermining the angular relation of the tip seam to said clamp members, and spring means for moving said jig pins in the direction to pull the forepart of the upper heightwise about one of said clamp members before the upper is clamped.

14. In a machine for shaping shoe uppers, the combination with means for shaping the heel-end portion of an upper over a form, of cooperating clamp members arranged to clamp the top 20 of the forepart of the upper between them and movable relatively to said form to pull the upper lengthwise, and means constructed and arranged to act by engagement with the marginal portion of the upper at the opposite sides of the forepart to subject the upper to a comparatively light pull lengthwise about the form and heightwise about one of said clamp members before the upper is clamped by said members.

15. In a machine for shaping shoe uppers, the combination with means for shaping the heel-end portion of an upper over a form, of cooperating clamp members arranged to clamp the top 30 of the forepart of the upper between them in the vicinity of the tip seam and movable relatively to said form to pull the upper lengthwise, jig pins arranged to engage the upper in jig holes provided therein substantially at the ends of the tip seam to predetermine the relation of the forepart of the upper to said clamp members, and spring means arranged to move said jig pins in directions both lengthwise and heightwise of the upper to pull it lightly about the form and also to pull its forepart lightly about one of said clamp members before the upper is clamped by 40 said members.

16. In a machine for shaping shoe uppers, the combination with means for shaping the heel-end portion of an upper over a form, of cooperating clamp members arranged to clamp the 50 forepart of the upper between them and movable relatively to said form to pull the upper lengthwise, and jig pins arranged to engage the mar-

ginal portion of the upper in jig holes provided therein at the opposite sides of the forepart and thereby to predetermine the relation of the forepart of the upper to said form and clamp members, said jig pins being movable with said clamp members in the pulling of the upper.

5

17. In a machine for shaping shoe uppers, the combination with means for shaping the heel ends of uppers of different sizes over heel-end forms of correspondingly different sizes, of upper-pulling means arranged to engage the forepart of each upper and movable to pull the upper lengthwise relatively to the form over which its heel end is shaped, and means arranged to be controlled by each heel-end form for positioning said upper-pulling means initially at a distance from the form determined by the size of the form.

10

18. In a machine for shaping shoe uppers, the combination with means for shaping the heel ends of uppers of different sizes over heel-end forms of correspondingly different sizes, of upper-pulling means arranged to engage the forepart of each upper and movable to pull the upper lengthwise relatively to the form over which 25 its heel end is shaped, a spring tending to move said upper-pulling means toward the form in a direction lengthwise of the upper, and a device arranged to be controlled by each heel-end form and to determine the limit of movement of the 30 upper-pulling means toward the form in accordance with the size of the form.

35

19. In a machine for shaping shoe uppers, the combination with means for shaping the heel ends of uppers of different sizes over heel-end forms of correspondingly different sizes, of upper-pulling means arranged to clamp the forepart of each upper and movable to pull the upper lengthwise relatively to the form over which 40 its heel end is shaped, members mounted for movement with said upper-pulling means and arranged to engage the upper in jig holes provided therein to position the upper initially in proper relation to the upper-pulling means, and a device movable to different positions in accordance with differences in the sizes of different forms and arranged to act as a stop to limit movement of said upper-pulling means and members toward the form and thus to determine their initial positions in accordance with the size 45 of the form.
